[57] **CLAIM**

The ornamental design for a body scrubbing device, as shown and described.

DESCRIPTION

FIG. 1 is a perspective view of my body scrubbing device;
FIG. 2 is a front view thereof;
FIG. 3 is a side view thereof;
FIG. 4 is a rear view thereof;
FIG. 5 is a top view thereof; and,
FIG. 6 is a bottom view thereof.

The broken line showing of features in FIGS. 1, 2 and 3 is for illustrative purposes only and forms no part of the claimed design.
